CLAIM

The ornamental design for a hot stick tool assembly, as shown and described.

DESCRIPTION

FIG. 1 is a perspective view of a hot stick tool assembly showing the new design.

FIG. 2 is a right side view thereof.

FIG. 3 is a left side view thereof.

FIG. 4 is a front view thereof.

FIG. 5 is a rear view thereof.

FIG. 6 is a top view thereof.

FIG. 7 is a bottom view thereof; and,

FIG. 8 is a reverse perspective view thereof.

The broken lines depict portions of the hot stick tool assembly that form no part of the claimed design.
